(57) **CLAIM**

The ornamental design for a fishing line control, as shown and described.

DESCRIPTION

FIG. 1 illustrates a front right-side perspective view of a fishing line control in an open position, wherein the fishing control is attached to a fishing rod, with a fishing line passing through the fishing line control;

FIG. 2 illustrates a front left-side perspective view of the fishing line control in a closed position;

FIG. 3 illustrates a front view of the fishing line control in the closed position;

FIG. 4 illustrates a rear view thereof;

FIG. 5 illustrates a left-side view thereof;

FIG. 6 illustrates a right-side view thereof;

FIG. 7 illustrates a top view thereof;

FIG. 8 illustrates a bottom view thereof;

FIG. 9 illustrates a front right-side perspective view of the fishing line control in the closed position and the fishing line being clamped by the fishing line control, wherein the fishing control is attached to the fishing rod;

FIG. 10 illustrates an exploded view of the fishing line control;

FIG. 11 illustrates a front view of the fishing line control in the open position;

FIG. 12 illustrates a rear view thereof;

FIG. 13 illustrates a left-side view thereof;

FIG. 14 illustrates a right-side view thereof;

FIG. 15 illustrates a top view thereof; and,

FIG. 16 illustrates a bottom view thereof.

The broken line showing of portions of the fishing line control is included for the purpose of illustrating only and forms no part of the claimed design.

1 Claim, 10 Drawing Sheets
